UNITED STATES PATENT OFFICE.

RUPERT ANDERSSON, OF SKARBLACKA, SWEDEN.

AUTOMATIC INTERRUPTER FOR ELECTRIC HEATING APPARATUS.

Application filed November 13, 1922. Serial No. 600,862.

To all whom it may concern:

Be it known that I, RUPERT ANDERSSON, a citizen of the Kingdom of Sweden, residing at Skarblacka, Sweden, have invented 5 new and useful Improvements in Automatic Interrupters for Electric Heating Apparatus, of which the following is a specification.

This invention relates to automatic 10 interrupters for electric heating apparatus, such as electric irons, electric stoves and similar apparatus.

The object of the invention is to provide 15 a simple and reliable interrupter of the said kind which will automatically open the circuit of the heating apparatus as soon as the heater reaches a predetermined temperature.

According to this invention the interrupter comprises a tubular member to be 20 put directly on a contact pin of the heating apparatus so as to be heated by heat transmission therefrom, a sleeve slidably mounted on said tubular member and normally secured in place thereon by means of a metal 25 or alloy having a low melting point, said sleeve having a laterally projecting contact arm adapted to engage a rigid fork-shaped contact member, when the sleeve is in normal position on the tube, while being 30 disengaged therefrom, when after reaching the predetermined temperature the metal or alloy is melted thereby releasing the sleeve, and the latter is thereupon displaced on the tube due to the action of a spring or its 35 own weight.

In the accompanying drawing one embodiment of the invention is illustrated. Figs. 1 and 2 are two longitudinal sections 40 of the interrupter at right angles to each other. Fig. 3 is a longitudinal section of a cartridge fuse for use in connection with the interrupter shown in Figs. 1 and 2. Fig. 4 is a cross section on line A—A, Fig. 1.

With reference to the drawing, the 45 numeral 1 indicates a block of insulating material, said block having at one end three openings 2, 3, 4 formed in it, the openings 3 and 4 communicating with each other through a longitudinally extending slot 5. Inserted in the opening 2 is a contact sleeve 6 adapted to be put directly on one contact 50 pin of a heating apparatus (not shown). Attached to the sleeve 6 is one leading-in wire 7. The opening 3 contains a fork-shaped contact member 8 to which the other

leading-in wire 9 is connected. The opening 4 is adapted to receive a cartridge fuse more clearly shown in Fig. 3.

The said cartridge fuse comprises an inner tube 10 adapted to be put on the other contact pin of the heating apparatus, and an outer tube or sleeve 11 the length of which is less than that of the tube 10. The sleeve 11 is capable of moving longitudinally on the tube 10 and carries a laterally projecting arm 12 adapted to engage the fork-shaped contact 8 above referred to. Provided outside the tube 10 at the ends thereof are annular stops 13 to limit the longitudinal movement of the sleeve 11 relatively to the tube 10. With the sleeve 11 abutting against one of the stops 13 a soft brass alloy, such as Woods alloy, is poured in between tube 10 and sleeve 11 which will thereby be secured in place relatively to each other.

Inserted in a reduced extension of the opening 4 at the bottom thereof is a flexible holding member 14 adapted to engage any of two notches 15 formed inside the tube 10 near the ends thereof. The holding member 14 may be controlled manually by means of a button 16. The opening 4 is also adapted to receive a helical spring 17 of an inside diameter corresponding to the outside diameter of the sleeve 11.

The cartridge fuse, described above, is inserted into the opening 4 with that end first at which the sleeve 11 is positioned and with the arm 12 engaging the slot 5. The cartridge is moved inwardly while compressing the spring till the arm 12 engages the fork 8 and the holding member 14 engages the respective notch 15 and locks the cartridge in position.

A metallic connection will now exist from the leading-in wire 9 through fork 8, arm 12, sleeve 11, and to the tube 10 by way of the alloy connecting the sleeve 11 to the tube 10.

The interrupter, when put on the contact pins of the heating apparatus, will thus close the circuit thereof. When the temperature of the heating apparatus and thus also that of the cartridge fuse has reached its predetermined maximum value which is dependent on the melting point of the alloy used to secure sleeve 11 to tube 10, this alloy will melt thereby releasing the sleeve 11 from the tube 10. The compressed spring 17 is now free to displace the sleeve 11.

the tube 10 outwardly till the outer end of the sleeve engages the outer stop 13 of the tube 10 and is stopped thereby. In this movement the arm 12 is released from the fork 8 thereby opening the circuit of the heating apparatus. The melted alloy accompanies sleeve 11 in the above said movement and hardening immediately upon the reduction of temperature will again bind sleeve 11 to tube 10 in the relative position in which the sleeve is at the outer end of the tube.

To again close the circuit of the heating apparatus the cartridge fuse should be removed from the opening 4 which may be effected by applying pressure to the button 16 which will then cause the holding member 14 to release the tube 10. The cartridge when cooled, may then be removed and turned to be again inserted in the opposite direction thereby again closing the circuit in the same way as that previously described.

It should be noted, that the interrupter described may be used in vertical and horizontal position as well as in any inclined position between vertical and horizontal.

Instead of the spring 17 to effect the displacement of the sleeve 11, when released, use may be made of the own weight of the sleeve for the same purpose. In such case, however, the interrupter cannot, of course, be used in any position.

What I claim is:—

1. An automatic interrupter for electric heating apparatus, comprising in combina-

tion an insulating base portion, a fixed contact sleeve carried by said base portion and connected to a current wire, another fixed contact member carried by said base portion and connected to another current wire, a tube, to be loosely inserted in said base portion, a sleeve slidably mounted on said tube and secured in place thereon by means of a soldering material having a low melting point, and a contact member on said sleeve adapted to engage said other fixed contact member and to be automatically moved out of engagement therewith, as soon as the soldering material melts. 40 45 50

2. An automatic interrupter for electric heating apparatus, comprising in combination an insulating base portion, a fixed contact sleeve carried by said base portion and connected to a current wire, another fixed contact member carried by said base portion and connected to another current wire, a tube, to be loosely inserted in said base portion, a sleeve slidably mounted on said tube and secured in place thereon by means of a soldering material having a low melting point, and a contact member on said sleeve adapted to engage said other fixed contact member and means for automatically moving said last mentioned sleeve on said tube, as soon as the soldering metal melts, to thereby bring the contact member thereof out of engagement with the corresponding fixed contact member. 60 65

In testimony whereof I have signed my name. 70

RUPERT ANDERSSON.
